ROAD OR PAVEMENT.

1,351,607.

Specification of Letters Patent. Patented Aug. 31, 1920.

Application filed May 1, 1919. Serial No. 293,965.

To all whom it may concern:

Be it known that we, JAMES V. BARRETT and THOMAS J. BARRETT, citizens of the United States, residing in Bordentown and 5 Fieldsboro, Burlington county, New Jersey, respectively, have invented certain Improvements in Roads or Pavements, of which the following is a specification.

Our invention relates to the construction 10 of roads, pavements and the like, and one object of our invention is to utilize in such road or pavement the naturally rounded rocks, large pebbles, and the like found in gravel beds or dredged from rivers or 15 streams; the same being utilizable up to a size not exceeding six or eight by twelve inches, with which may be combined a certain amount of broken stone, graduated in size to that passing a two or two-and-one- 20 half inch ring and normally employed as the road metal in the construction and formation of macadam, telford, or bitulithic roads; the whole being bonded into a solid 25 concrete mass or body by the addition of a suitable proportion of hydraulic cement, gravel, sand, stone screenings, and the like, with the addition of water in proper and suitable proportion.

The larger material is designed to form 30 the sub-base or first layer deposited or placed upon the excavated roadbed, and before the cementing or concreting additions of such sub-base or layer are completely set, it is to receive a second layer of concrete, 35 approximately three inches in thickness, made from hydraulic cement, broken stone, pebbles and the like, the larger portions of which aggregate should preferably pass a two inch ring, and on top of this, a layer of 40 concrete, approximately three inches in thickness, is to be placed, in which the mineral aggregate is considerably finer and consists largely of fine pebbles, sand, small broken stone, and the like, with the proper 45 quantity of hydraulic cement and the necessary water. In preparing the several layers of concrete, they should be fairly wet to insure complete filling of the voids by the finer portions of the aggregate, and to 50 insure also that the several layers will be firmly bonded or tied together in a solid and substantially homogeneous mass.

The total thickness of the road or roadbed thus prepared may be approximately 55 twelve inches, of which the base consisting

of the larger pieces of mineral aggregate— cobble stones, broken stone and the like, may be at least six inches in thickness, and the subsequent layers or those parts of the road which are laid as layers; being finally 60 bonded into a homogeneous mass by the cementing material present, may approximate three inches each, or a total of approximately twelve inches; the material of the road being progressively finer from the 65 sub-base to the wear surface of the same.

A further feature of our invention is the provision of wheel treads or trackways in the surface of the road, which are designed to receive asphaltic, tarry, or bituminous 70 material, preferably material containing a relatively large proportion of mineral matter, and this asphaltic or composition trackway, of whatever material it may be composed, is to receive a metallic reinforce, 75 which may extend from the finished surface of the material forming the trackway to the bottom of the recess formed in the wear surface of the concrete road. Preferably, this metallic reinforce is in the form of a 80 continuous strip of metal, with its ends anchored in the concrete, and it may be made of bars having a cross sectional contour of such a character as to interlock with the concrete as well as with the asphaltic 85 material filling the recesses and constituting the wheel trackways of the roadbed. Instead of pouring the asphaltic, tarry, or bituminous material, we may prepare the same 90 in the shape of preformed slabs or strips of suitable length and proper width and thickness, which slabs or strips are prepared with a metallic reinforce of suitable character.

The special trackways may be approximately twenty inches in width, or any other 95 desired width, with concrete spaces between them of approximately forty-one inches or other suitable dimensions that will properly accommodate the wheel treads of various trucks and other vehicles using such form 100 of road.

These and other features of our invention are more fully described hereinafter, reference being had to the accompanying drawings, in which:

Figure 1, is a perspective view, partly in section, of a roadway built in accordance with our invention, showing also the trackways formed in the surface of the same.

Fig. 2, is a plan view of one form of me- 110

tallic reinforce which may be employed in such trackway.

Fig. 3, is a cross sectional view of the same.

5 Fig. 4, is a sectional view illustrating a trackway having a relatively shallow reinforce and special supporting means for the same.

10 Fig. 5, is a perspective view showing the use of protective edge strips for the recesses receiving the composition to form the trackways.

15 Fig. 6, is a similar view showing reinforcing members combined with the protective edge strips.

Fig. 7, is a plan view of a road or pavement having trackways made up of preformed slabs of asphaltic, bituminous, or tarry material.

20 Fig. 8, is a perspective view of one type of preformed slab within the scope of our invention, and

25 Fig. 9, is a perspective view of one form of metallic reinforce within the scope of our invention which may be employed with the preformed slabs.

30 In building a road in accordance with our invention, we propose to employ for the lower portion of the base of the same, generally indicated at 1, the larger rounded cobbles or pebbles from natural sand banks or dredged from river sand beds, which may be of a size not exceeding six inches in one dimension, in order that such base may approximately come within such dimension, with which may be combined broken stone of various sizes and dimensions to fill the voids between such cobbles or pebbles, and then the whole surface receives a mixture of

35 40 finer aggregate, which may include sand, stone screenings, hydraulic cement and water, in order that all of the voids of such base may be filled and a solid concreted body developed. It will be understood, of course that prior to placing the material to form the sub-base, the roadway will be excavated to the proper depth and properly prepared to receive the same.

45 In constructing such sub-base, the concreting material may be placed on dry and raked into the voids, after which water may be applied and the whole rolled with a heavy roller; additional material being supplied as fast as the plastic or liquid portions thereof 50 55 pass into the voids, until a substantially solid, voidless base or sub-base is prepared, which is preferably of a thickness approximating six inches, more or less. This sub-base is thoroughly compacted by rolling; a very heavy roller being preferred.

60 The concreting materials of the base or sub-base 1 should be kept in a wet or green condition until the second layer of concreting material is spread upon the first. Such 65 second layer of material, generally indicated

at 2, may include pebbles, and broken stone passing a two inch ring, with a suitable addition of sand, smaller broken stone, hydraulic cement, and the like, and, preferably, this material is prepared in an ordinary concrete mixer and dumped on the main base or sub-base 1 as soon as the latter is thoroughly compacted. The second layer is subsequently rolled to a thickness approximating three inches. While this second layer is still in a moist or green condition, the final layer of concrete, generally indicated at 3, and which may consist of cement, sand, stone screenings and fine pebbles, with the proper amount of water, is 70 75 laid; bringing the road to the proper height or crown to constitute the finished surface, and this layer is spread and finished in any usual or approved manner and thoroughly rolled until a completely dense layer with a 80 85 relatively smooth wear surface 4 is provided.

90 In preparing the wear surface of the road, we provide for the formation of special trackways 5, of asphaltic, bituminous, or tarry material, by placing suitable planks or other means designed as spacers to form recesses 6 in the finished road surface, and such recesses may be approximately two inches in depth, by twenty inches in width, or any other suitable dimensions, extending 95 lengthwise of the road and spaced approximately forty-one inches apart, or any other width that will properly accommodate the traffic. Four of such trackways are preferably provided so that the traffic may have 100 specially prepared trackways or paths in both directions which are intended to keep the traffic on proper sides of the road in both directions.

105 In order that the material employed may firmly knit to the bottom of the trackways, such bottom surfaces are left relatively rough, as indicated at 4^a, and in order to increase the wearing ability of such asphaltic material, we preferably include metallic reinforcing means in the same. This may be in the form of a continuous bar 7, 110 bent upon itself substantially in serpentine fashion, as illustrated in the drawings, so as to constitute a wear-resisting element 115 substantially continuous with the trackways, and it may be of a thickness extending to the bottom of the recess, or the recess may be provided with bars 8, extending longitudinally of the same, as indicated in Fig. 4, 120 upon which a narrower metallic reinforce 7^a may rest whereby its upper surface is brought substantially flush with the finished surface of the roadway. If desired, the reinforcing strip may be apertured so that the 125 material constituting the trackways may be interlocked therewith.

130 In forming these recesses in the concrete surfaces, it may be desirable to round the edges of the concrete walls to avoid chip-

ping the same, or in lieu of this nosing strips 9, which may be of metal, may be employed, as shown in Fig. 5, between which the asphaltic, bituminous, or tarry material 5 may be laid to fill the recesses. Additionally, these nosing strips may carry lateral projections 10 to serve as reinforcing means, as shown in Fig. 6, which may lie in the upper portion of the asphaltic, bituminous, or tarry body and take the place of the serpentine reinforcing material formed by the bars 7, or the projections 10 may extend to the bottom of the recesses.

When the serpentine reinforce is employed, it may have a narrow cross sectional contour with concaved sides 7^b, as shown in Fig. 3, whereby it will be interlocked with the asphaltic, bituminous, or tarry material employed, and preferably the free ends 7^c 15 of the same are bent out and downwardly and anchored in the side walls, or other portion of the concrete, so as to insure against projection from the roadbed and avoid danger of puncturing tires or otherwise damaging wheels or other parts of vehicles passing over the roadway.

In the form of trackways as proposed with reference to the form of road shown in Fig. 1, our object has been to provide recesses in the upper portion or wear surface of the concrete road which subsequently receive the composition or other material of an asphaltic, bituminous, or tarry nature comprising such trackway.

35 In lieu of this method of procedure, we may employ preformed slabs of asphaltic, bituminous, or tarry material, of suitable dimensions, as shown at 11 in Figs. 7 and 8, with which may be combined suitable metallic reinforcing means in the form of serpentine or other strips 12. These slabs may be laid during the building of the top layer of the road in such position as to come flush with the top surface; the concreting material forming such top surface being poured upon and adjacent to these strips while they are held in proper position with respect thereto to form the desired trackways longitudinally of the road. For this 40 purpose, strips of wood or metal 13 may be laid in the concrete and properly stayed by braces 14 or other means between which the preformed slabs may be placed, or such slabs may be anchored in position by any 45 suitable means, or any other method of procedure that will insure the proper disposal of the slabs with respect to the road may be employed.

The concrete will be laid right up against 50 the slabs, and if the spacing strips 13 are employed, they may be removed prior to the setting of the concrete and the spaces occupied thereby properly filled in. If metallic spacing strips are employed, they may be 55 left in the roadbed and form reinforced

shoulders for the concrete to prevent the edges of the same breaking down.

The metallic reinforcing means for the slabs may be in the form of bars extending lengthwise or crosswise of the slab, or a substantially serpentine reinforce may be employed, as indicated in Figs. 7, 8 and 9. This reinforce may have its ends 12^a projecting, preferably downwardly and outwardly, so as to be embedded in the concrete, thereby tying the concrete roadbed to such preformed slabs or the reinforcing portion thereof, and anchoring the ends against damage to the traffic. In some instances, it may be desirable to provide the metallic reinforce with apertures 15, as shown in Fig. 9, so that the asphaltic, bituminous, or tarry material constituting the slab may interlock with the reinforce and hold the same securely in place.

75 The trackways being filled with asphaltic, bituminous, or tarry material will, in a large measure, constitute longitudinal expansion joints for the roadway, preventing lateral displacement of the same; it being understood, of course, that the usual type of expansion joints disposed laterally with respect to the road are also employed.

80 A particular advantage resides in the use of the naturally rounded rocks and large 90 pebbles found in sand banks or dredged from rivers, creeks, and other water courses, in that such form of mineral aggregate is of solid, dense formation. Stone removed from rock formation is usually, if not always, obtained by the use of an explosive, and in addition to breaking the same from its natural base, each portion removed has been subjected to stresses and strains which frequently leave it with cracks and fissures 95 which cannot stand up under the strains imparted to it when employed in road construction. This is inevitably true of the larger pieces of such form of mineral aggregate. It is, of course, much less so of the 100 smaller pieces or those passing a ring two or two-and-one-half inches in diameter; the usual means employed for testing for size. While the smaller portions of mineral aggregate may be usefully employed to fill the 105 voids between the large rocks or pebbles, and also as a definite portion of the intermediate layer of the concrete roadbed, we 110 specifically wish to avoid the use of large sections of broken stone as any part of the 115 relatively thick base or sub-base of our improved road which, when concreted together in a homogeneous mass with its voids filled, forms a solid footing or foundation, usually 120 arched across the road and providing a most substantial support for the main body and 125 wear surface of the road.

130 From the foregoing, it will be seen that we have provided a road comprising a solid mass of concrete approximately twelve

inches in thickness, in which the mineral aggregate is graduated in size from the sub-base to the top surface of the roadbed, and wherein all or substantially all of the voids 5 are filled with concreting material.

Additionally, we have provided such a roadbed with trackways having a cushioning value that will greatly relieve the stresses and strains applied to the road by the traffic, 10 and additionally we have provided these trackways with reinforcing means so that the life of the same is equal to or greater than that of the road.

It will be understood, of course, that in 15 the building of such a road, expansion joints will be provided at more or less definite intervals to insure compensation for any strains which may be set up in the road during construction or after the same is 20 built; all of which is within the scope of the general art of road building.

While we have described the use of these special trackways in a specially built concrete road, it will be understood that it is 25 entirely practicable to construct such trackways in various kinds of roads already in use by scoring and excavating or otherwise removing portions of the surface of the same in paralleling lines, and then filling in such 30 recessed portions with composition material of an asphaltic, bituminous, or tarry nature, or with the preformed slabs illustrated in Figs. 7 and 8.

In resurfacing such forms of roads, it may 35 be desirable to put concrete curbings or copings, or metallic strips directly adjacent the bodies of material forming the trackways, with any suitable form of paving—macadam, telford, bitulithic, or the like, between 40 such trackway strips, or between the curbing or coping supporting the same; all of which is within the scope of our invention.

While we have shown specific embodiments of the various details of our invention, 45 it will be understood that they are largely for illustrative purposes, and that various modifications of the same entirely within the scope of our invention may be substituted therefor, all of which is within the 50 scope of the appended claims.

We claim:

1. A concrete roadway or pavement having 55 a recess extending lengthwise of the wear surface of the same and of substantially uniform depth, a filling of asphaltic, bituminous, or tarry paving material in said recess, and metallic reinforcing strips interlocked with said paving material; the projecting ends of said metallic reinforcing strips being embedded in the body of the road.

2. A roadway or pavement having longitudinal recesses in its surface, guards protecting the edges of said recesses, and pre- 65 formed slabs of elastic or cushioning paving

material filling said recesses and lying flush with the surface of the road.

3. A roadway or pavement having longitudinal recesses in its wear surface, guards protecting the edges of said recesses, pre- 70 formed slabs of elastic or cushioning paving material filling said recesses and lying flush with the surface of the road, and metallic reinforcing means carried by said slabs and extending from top to bottom of the same. 75

4. The combination of a roadbed having its surface provided with a plurality of recesses, asphaltic, bituminous, or tarry material filling said recesses, and metallic reinforcing means therefor, the ends of which 80 reinforcing means are embedded in the roadbed.

5. The combination with the wear surface of a roadway, of paralleling trackways extending longitudinally of such roadway 85 and comprising elastic paving material with metallic reinforcing means therein; the reinforcing means being in the form of continuous strips with its end portions anchored in the roadway. 90

6. A concrete roadway or pavement having a recess extending lengthwise of the wear surface of the same and of substantially uniform depth, preformed slabs of asphaltic, bituminous, or tarry paving material in said recess, and metallic reinforcing strips interlocked with the paving material of said preformed slabs; the projecting ends of said metallic reinforcing strips being embedded in the body of the road. 100

7. The combination of a roadbed having its surface recessed, metallic nosing strips for the edges of said recesses, a body of asphaltic, bituminous, or tarry paving material filling said recess and flush with the surface of the roadbed, and metallic reinforcing means extending through said paving material. 105

8. The combination of a roadbed having its surface recessed, metallic nosing strips for the edges of said recesses, preformed slabs of asphaltic, bituminous, or tarry paving material filling said recess and flush with the surface of the roadbed, and metallic reinforcing means extending through said 110 preformed slabs of paving material. 115

9. The combination of a roadbed having its surface provided with a plurality of paralleling recesses, metallic nosing strips for the edges of said recesses, asphaltic, bituminous, or tarry paving material filling said recesses and flush with the surface of the roadbed, and metallic reinforcing means therefor extending through said paving material; the ends of which reinforcing means 120 are embedded in the roadbed. 125

10. The combination of a roadbed having its surface provided with a plurality of paralleling recesses, metallic nosing strips for the edges of said recesses, preformed slabs 130

of asphaltic, bituminous, or tarry paving material filling said recesses and flush with the surface of the roadbed, and metallic reinforcing means therefor extending through 5 said preformed slabs of paving material; the ends of which reinforcing means are embedded in the roadbed.

11. The combination with the wear surface of a roadway, of paralleling trackways 10 extending longitudinally of such roadway and comprising longitudinal metallic strips bounding said trackways and elastic paving material with metallic reinforcing means embedded therein disposed between said 15 longitudinal metallic strips.

12. The combination with the wear surface of a roadway, of paralleling trackways extending longitudinally of such roadway and comprising longitudinal metallic 20 strips bounding said trackways and preformed slabs of elastic paving material with metallic reinforcing means embedded therein disposed between said longitudinal metallic strips.

13. The combination with the wear surface of a roadway, of paralleling trackways extending longitudinally of such roadway and comprising longitudinal metallic strips bounding said trackways and elastic paving material with metallic reinforcing means 25 embedded therein disposed between said longitudinal metallic strips; the reinforcing means being in the form of continuous strips with their end portions anchored in the roadway. 30

14. The combination with the wear surface of a roadway, of paralleling trackways extending longitudinally of such roadway and comprising longitudinal metallic strips bounding said trackways and preformed 40 slabs of elastic paving material with metallic reinforcing means embedded therein disposed between said longitudinal metallic strips; the reinforcing means being in the form of continuous strips with their end 45 portions anchored in the roadway.
